W Scott Keeley(57) **CLAIM**

The ornamental design for a cap with locks of hair, as shown and described.

DESCRIPTION

FIG. 1 is a front, left side perspective view of a cap with locks of hair shown in a position of use;

FIG. 2 is a rear perspective view of the cap with locks of hair;

FIG. 3 is a front elevation view thereof;

FIG. 4 is a right side elevation view thereof, the left side being a mirror image thereto;

FIG. 5 is a rear elevation view thereof;

FIG. 6 is a top plan view thereof; and,

FIG. 7 is a bottom plan view thereof.

The broken-line outline of the partial human figure assists in illustrating how the claimed design may appear when worn, but forms no part of the claimed design. The even length broken lines within the interior crown portion of the cap with locks of hair depict portions of the article that form no part of the claimed design. The dash-dot-dash broken lines and areas within the dash-dot-dash broken lines define portions of the cap with locks of hair that form no part of the claimed design.
